UNITED STATES PATENT OFFICE

2,508,703

BRASSIÈRE

Victor I. Becker, Los Angeles, Calif.

Application February 14, 1948, Serial No. 8,475

6 Claims. (Cl. 2—42)

1

This invention relates to brassières and has for its primary object the provision of a garment of this character in which certain desirable advantages to be hereinafter pointed out will be secured.

At the present time attempts are made to reinforce and strengthen certain portions of brassières so as to impart to the breast pockets a round or circular conformation to thereby shape or mould the breasts to conform thereto. Such reinforcement of the breast cups is often attempted by the provision of concentric lines of stitching arranged in circular paths with the center of the breast cup constituting the center of the circularly-arranged lines of stitching. While such an arrangement of stitching is effective in maintaining the breast cup in a well-defined circular form, it provides an equality of reinforcement all around the cup and which is not the optimum of efficient support for the breasts.

The present invention, therefore, contemplates the provision of stitching in the breast cup which defines a circular form in the breast cup and which, in addition, has tangential extensions disposed to one side of the vertical center line of the breast cup, and extending to the upper and lower edges of the brassière, whereby there is provided in the outer side portion of each breast cup, a strongly reinforced area tending to materially restrain outward distortion of the breast cups, thus restraining outward spread of the breasts while maintaining the same in the desired circular conformation.

More particularly, the invention contemplates the provision of a brassière having breast cups in each of which is provided a plurality of closely spaced, substantially parallel lines of stitching which begin at the upper edge of the brassière at one side of the center line of the breast cup and then pursue a circular path around the breast cup, with the center of the cup constituting the center of the concentric lines of stitching, said lines of stitching then extending downwardly to the lower edge of the brassière, the lower terminations of the lines of stitching being also to one side of the center line of the breast cup and at the same side of the cup as that in which the upper terminals of the lines of stitching are located.

These and other objects are attained by the invention, a more particular description of which will hereinafter appear and be set forth in the claims appended hereto.

In the accompanying drawing, wherein an ill-

2

lustrative embodiment of the invention is disclosed:

Fig. 1 is a front elevational view of the portion of a brassière that is constructed according to the invention and,

Fig. 2 is an enlarged front view of one of the breast cups showing the novel reinforcing stitching employed therein.

With reference to the drawing 1 and 2 indicate the two breast cups of the brassière, the same being shown connected together by means of the triangulated elastic insert 3, in the known manner. Each of the breast cups may be composed of one or more layers of fabric connected together in overlying relation, and each cup is formed in the required cupped conformation by the joinder together of segmental sections of fabric, by goring, or other means known in this art.

To maintain the breast cups, or at least the major central area thereof, in the desired circular form, reinforcing stitching is provided. This stitching consists of a plurality of substantially parallel, closely spaced lines of stitching 11 defining a plurality of concentric circles 4 in the breast cup with the central point or extremity 10 of the breast cup constituting the center point of the circles 4. Each of the lines of stitching has its upper termination at the upper edge of the breast cup as indicated at 5, while the lower end of each line of stitching extends to the lower end of the breast cup as indicated at 6. The result of this arrangement is that the lines of stitching 11 cooperate in defining a reinforced circular area in the central part of the cup from which tangential extensions 12 and 13 are directed, which extensions extend both upwardly and downwardly to the upper and lower edges of the brassière as indicated at 5 and 6 respectively.

It will be observed that through this arrangement, a strongly reinforced area is provided in each breast cup and particularly in that portion of the cup wherein distension or spread of the cup is undesirable. That is to say, it is the desire and intention of the improved structure to not only support and mold or shape the breast into approved contour and in performing this function to restrain the breast against the laterally spreading tendency, this spread being retarded materially by stiffening or reinforcing the breast cups within the area in which the greatest tendency to spread exists, namely at the outer sides of the breasts beyond the vertical center line of the breast cup, such line being indicated at 8 in Fig. 1.

By the arrangement of the stitching in the manner described and wherein the lines of stitching intersect in the outer side of each of the breast cups and beyond the vertical center line of the cup, a quilted stitching effect is provided in this area as indicated at 1 so that a greater reinforcement and tendency to prevent distortion of this portion of the cup will be present.

It will thus be clear that while the breast cups will be strongly reinforced and held against undesirable expansion and distortion in those areas where such effects are not desired, the reinforcement and strengthening of the brassière in those areas is attained by the expedient of utilizing stitching rather than by the addition of extra plies or inserts of fabric. The result is that a lightweight, cool and comfortable brassière is produced which will nevertheless provide a maximum of support and restraint for the bust.

While I have shown one embodiment of the invention, it is obvious that various changes may be made without departing from the spirit of the invention. For example, while the lines of stitching in the breast cups are shown to be equally spaced apart, the spacing of these lines of stitching might be varied; the general shape and construction of the breast cups might also be materially changed and other changes made as will be apparent to those skilled in this art.

What I claim is:

1. A brassière having a breast cup provided with a plurality of closely spaced lines of stitching encircling the apex of the cup, one end of each line of stitching starting at the upper edge of the breast cup to one side of the vertical center line of the cup, and the opposite end of each line of stitching being located at the lower end of the cup and also to one side of the vertical center line of the cup.

2. A brassière as provided for in claim 1, wherein both ends of all of the lines of stitching are located at the same side of the vertical center line of the breast cup.

3. A brassière as provided for in claim 1, wherein the ends of the lines of stitching are located at the same side of the vertical center line of the breast cup, said side of the cup being the outer side thereof.

4. A brassière having a breast cup provided with a plurality of closely spaced lines of stitching encircling the cup and defining a circular

path around the center point of the cup, said lines of stitching having tangentially extending ends terminating respectively at the top and bottom edges of the brassière.

5. A brassière having a breast cup reinforced by a plurality of lines of stitching, said lines of stitching extending parallel to one another and have ends beginning at the top edge of the brassière and thence proceeding in a circular

10 path around the breast cup, said lines of stitching then extending tangentially downwardly to terminate at the lower edge of the brassière, said lines of stitching crossing one another, the crossing points of said lines of stitching as well as the 15 upper and lower ends of said lines of stitching being located to one side of the vertical center line of the breast cup.

6. A brassière having a breast cup provided with a plurality of closely-spaced substantially 20 parallel lines of stitching beginning at the upper edge of the brassière at one side of the vertical center line of the cup, said lines of stitching extending in concentric relation in a circular path around the breast cup with the center of the cup 25 constituting the center of the circles defined by the lines of stitching, said lines of stitching extending downwardly to the lower edge of the brassière, the lower terminations of the line stitching being also to one side of the vertical center line of the brassière and located at that 30 side of the cup in which the upper ends of the lines of stitching are located.
